UNITED STATES PATENT OFFICE

93,419

DESIGN FOR A PLAYING CARD HOLDER

Richard Charles Ostrowski, North Weymouth,
Mass.

Application June 21, 1934, Serial No. 52,258

Term of patent 7 years

To all whom it may concern:

Be it known that I, RICHARD CHARLES OSTROWSKI, a citizen of the United States, residing in North Weymouth, in the county of Norfolk and Commonwealth of Massachusetts, have invented a new, original, and ornamental Design for Playing Card Holder, of which the following is a specification, reference being had to the accompanying drawing, forming part thereof.

Fig. 1 is a plan view of the playing card holder showing my new design; and Fig. 2 is a side elevation of the same.

I claim:

The ornamental design for a playing card holder, as shown.

RICHARD CHARLES OSTROWSKI.
